UNITED STATES PATENT OFFICE.

HENRY W. YOUNGQUIST, OF MANCHESTER, NEW HAMPSHIRE.

FEELER MECHANISM FOR LOOMS.

1,122,838.

Specification of Letters Patent. Patented Dec. 29, 1914.

Application filed August 5, 1914. Serial No. 855,290.

To all whom it may concern:
Be it known that I, HENRY W. YOUNGQUIST, a citizen of the United States, residing at Manchester, county of Hillsboro, State 5 of New Hampshire, have invented an Improvement in Feeler Mechanism for Looms, of which the following description, in connection with the accompanying drawing, is a specification, like characters on the drawing 10 representing like parts.

The invention relates to improvements in feeler mechanism for automatic filling replenishing looms and its principal object is to permit the adaptation of the usual Northrop type of loom to filling carriers having 15 slots in their barrels to receive the end of the feeler on substantial exhaustion of filling upon the filling carrier, thus avoiding the necessity of using filling carriers having 20 specially wound feeler bunches.

Another object of the invention is to provide a simple and effective feeling mechanism for looms constructed of relatively few elements and in such a manner that the same 25 will work accurately and will be unlikely to become broken or damaged in use and if broken may be repaired easily.

Other objects of the invention and the nature thereof will more fully appear from the 30 following description and accompanying drawings and will be particularly pointed out in the annexed claims.

In the drawings, Figure 1 is a plan view, centrally broken away, of a portion of an automatic replenishing loom embodying a preferred form of my invention; Fig. 2 is a front elevation of the shipper stand, the feeler, and the controller which is actuated thereby to initiate the change in the operation 40 of the loom, and Fig. 3 is a side elevation of my improved feeler and its stand detached from the loom and looking from the center of Fig. 2 toward the right.

A preferred form of my invention is illustrated herein as applied to the usual Northrop type of filling replenishing looms, parts 45 of which as illustrated in Fig. 1 comprise a lay 1, having shuttle boxes 2 and 3 at opposite ends of said lay, a shuttle 4 containing a filling carrier 5 provided with a feeler slot 6 50 adjacent to its base, the side of the shuttle box being provided with a slot 7 in alignment with slot 6 in the bobbin to receive the feeler as the lay moves forward to beat up 55 the filling. The shuttle box 3 passes beneath the usual hopper or battery 8 and the loom

is provided with a transfer arm 9 adapted to be actuated in the usual manner to insert a new filling carrier in an active shuttle through a controller shaft 10, extending longitudinally of the breast beam 11 and journaled in suitable bearings depending therefrom.

As illustrated herein the loom is provided with a weft fork 12 and the ordinary mechanism actuated thereby to cause a stoppage of the loom or to effect transfer of the filling carriers upon the breaking of the filling.

The usual shipper stand 13 is shown at the left end of the loom with a slot 14 to receive the shipper 15 and the knock-off lever 16 pivotally mounted upon the breast beam, one end of said knock-off lever engaging the shipper 15 and the opposite end lying in position to be actuated by the usual automatic stop mechanism.

As is well known, the feeler may be utilized either to effect the stoppage of the loom by causing the engagement of the knock-off lever with a movable member placed in the path of a vibrating actuator, or may be utilized to cause the automatic replenishment of the shuttle upon the substantial exhaustion of the filling in the shuttle. In either case the operation is usually initiated through 80 a controller having arms 17 and 18 extending from a hub 19 by means of which, it is pivotally supported upon a stud 20 projecting laterally from a suitable stand 21 which may be mounted upon the breast beam or 90 upon the shipper stand.

As illustrated herein the feeler mechanism is adapted to cause the automatic replenishment of the shuttle and the arm 17 of the controller extends beneath the end of a latch 95 22 which is pivotally mounted at its opposite end upon an arm 23 projecting upwardly from the controller shaft 10, said latch 22 being adapted to be raised by the arm 17 of the controller into the path of a vibrating actuator 24, which desirably may be the weft hammer.

The loom thus far described, is of the usual construction and the arm 17 of the controlling lever is ordinarily raised to initiate the action of the transfer mechanism by the depression of the opposite end 18 of the controller.

In the usual feeler mechanism of the Northrop loom the feeler engages the filling 110 on the filling carrier upon the forward movement of the lay and is thrust outward

in such a manner that the controller is not operated so long as a predetermined amount, usually a specially wound bunch of filling remains upon the carrier. If however the 5 yarn upon the filling carrier is exhausted below said predetermined amount a bunter pivotally supported upon the feeler contacts with the side of the shuttle box and thereby causes the actuation of means for depressing 10 the end of the controller arm 18 as the lay beats up so that the controller arm 17 is forced upwardly and the change of the operation of the loom effected. In the usual form 15 of feeler, the bunter is carried by the feeler and moves with the same upon each forward movement of the lay, the bunter being engaged by the shuttle box only when the filling is substantially exhausted.

The principal feature of this invention 20 comprises broadly, an oscillatory and reciprocable actuator connected both with a feeler, adapted to enter the shuttle and feel upon the filling carrier therein, and with the bunter adapted to be engaged by the shuttle 25 box or other mechanism carried by the lay or moved in synchronism therewith, the connections between the feeler and bunter and the actuator being such that the contact of the filling with the feeler will cause the 30 oscillation of the actuator out of operative relation to the controller while the actuation of the bunter alone will result in the reciprocation of the actuator and the consequent movement of the controller as afore- 35 said.

In the mechanism illustrated herein, the feeler mechanism comprises a stand 25 which preferably is provided with a slot 26 by means of which it may be secured to the 40 end of the breast beam or shipper stand 13, by bolts or other suitable fastenings, said stand having a forward extension 27 which desirably may be provided with a cap plate 28, said forward extension or stand having 45 cylindrical apertures or grooves adapted to receive and to form bearings for the stem 29 of the bunter 30 and for the feeler 31 so that the bunter and feeler will have direct 50 parallel reciprocatory movements when engaged respectively by the side of the shuttle box and the filling upon the filling carrier. The forward extension 27 of the feeler stand is desirably provided with a lateral flange 55 32 in front of which the end of the controller 18 rests. The feeler and the bunter are each independently connected to an oscillatory and reciprocable actuator 33 which is provided with an extension normally resting against the flange 32 and thereby positioned to engage the end of the controller 60 arm 18, whereby the reciprocation of the actuator will depress the controller arm 18 to initiate the action of the transfer mechanism or to effect such other change in the 65 operation of the loom as may be found de-

sirable while the oscillatory movement of said actuator will remove it from operative relation to the end of the controller arm 18 so long as the filling on the filling carrier is not substantially exhausted.

The actuator desirably may be pivotally supported at its lower end upon a stud 35 extending laterally from the end of the arm 36 of a bell crank lever which is pivotally mounted upon a stud 37 carried by an extension 38 of the stand 25, the other arm 39 of the said bell crank lever being provided with a stud 40 engaging a slot 41 in a block 42 rigidly secured upon a stem 29 of the bunter 30. It will be obvious that by reason of the construction aforesaid the actuation of the bunter alone will cause the bell crank lever to rock about its pivot 37 carrying downward the stud 35 upon which the lower end of the actuator 33 is pivoted, thereby depressing the end 34 of the actuator and with it the end of the arm of the controller 18, and initiating a change in the 80 operation of the loom.

In order to provide for the removal of 90 the actuator 33 from operative relation to the end of the controller arm during the normal running of the loom, the feeler 31 desirably may be provided with the downwardly and upwardly bent end portion 43, 95 providing a slot 44 adapted to receive a stud 45 projecting laterally from the actuator substantially in line with the feeler 31. The actuator 33 and the bell crank lever may be held in, and returned to feeling position 100 by means of suitable springs such as coiled springs 46, 47 surrounding respectively the pivots of the actuator and the bell crank lever and suitably connected thereto and to relatively stationary members.

By reason of the construction aforesaid, it will be apparent that when the feeler is engaged by the filling upon the filling carrier as the lay beats up the actuator will be oscillated either previously to or simultaneously with the engagement of the bunter with the shuttle box so that the end 34 of the actuator will follow an arcuate path away from the flange 32 and out of operation relative to the arm 18 of the controller, thus during the normal operation of the loom providing means which will avoid the possibility of an improper transfer or other change in the operation of the loom. Upon exhaustion of filling in the filling carrier 110 the feeler 31 will enter the slot 6 in the filling carrier and will not be retracted by the forward movement of the lay. The bunter 30 will then alone be engaged and will cause the reciprocation of the actuator 33 to initiate the transfer or other change 115 in the operation of the loom in the manner aforesaid.

It will be obvious that the feeler above described may be incorporated in any of the

Ordinary types of Northrop loom or may be substituted readily for the usual type of Northrop feeler, thus adapting the loom to be operated with bobbins having slotted barrels.

It is to be understood that the embodiment of the invention disclosed herein is illustrative merely and that various modifications thereof may be made within the scope of my invention as defined by the claims herein.

Having fully described my invention what I claim as new and desire to obtain by Letters Patent, is:

- 15 1. In a loom having means for causing a change in the operation of the loom upon substantial exhaustion of filling in an active shuttle including a controller, an oscillatory and reciprocable actuator therefor, a feeler, means connecting said feeler to said actuator adapted to oscillate said actuator from operative relation to said controller when the feeler is engaged by the filling in the shuttle, and means independent of 25 said feeler connected to said actuator adapted to reciprocate said actuator upon detection by the feeler of substantial exhaustion of filling and thereby to actuate said controller.
- 30 2. In an automatic loom having means for causing a change in the operation of the loom upon substantial exhaustion of filling in an active shuttle including a controller, a laterally oscillatory and vertically reciprocable actuator operatively mounted adjacent to said controller and adapted in its reciprocatory movement to engage and actuate said controller and upon its oscillatory movement to be removed from operative relation to said controller, a feeler connected to said actuator adapted to impinge upon and be moved by the filling within the shuttle and thereby to impart oscillatory movement to said actuator, a bunter adapted to engage the shuttle box and means for causing the same to impart a reciprocatory movement to said actuator and thereby to actuate said controller upon detection by the feeler of substantial exhaustion of the filling.
- 35 3. In an automatic filling replenishing loom having means for causing a change in the operation of the loom including a controller, a spring-controlled oscillatory and reciprocable actuator for said controller, a bunter adapted to engage the shuttle box upon each forward movement of the lay, a feeler adapted to engage the filling in the shuttle and independent means connecting said bunter and said feeler to said actuator whereby the simultaneous engagement of the bunter and feeler will cause the oscillation

of the actuator out of operative relation to said bunter, while engagement of the bunter alone upon detection by the feeler of substantial exhaustion of filling, will cause reciprocatory movement of said actuator to operate said controller.

4. In an automatic filling replenishing loom provided with filling carriers having slotted barrels and having means for causing a change in the operation of the loom including a controller, a bell crank lever, an oscillatory and reciprocable actuator pivotally mounted upon one arm of the bell crank lever, a bunter adapted to engage the shuttle box upon the forward movement of the lay connected to the other arm of said bell crank lever, a feeler connected to said actuator adapted to enter the shuttle and impinge upon and be moved by the filling therein and thereby to oscillate the actuator out of operative relation to said controller, but adapted to enter the slot in the filling carrier upon substantial exhaustion of the filling, whereby said actuator will be reciprocated by the bunter to actuate said controller.

5. In an automatic filling replenishing loom having means for causing a change in the operation of the loom including a controller, feeler mechanism comprising a feeler and a bunter slidably mounted in parallel bearings in a suitable supporting stand, an oscillatory and reciprocable actuator, and independent means connecting said actuator to said feeler and said bunter whereby the simultaneous actuation of the feeler and bunter will cause the removal of said actuator from operative relation to said controller and the actuation of the bunter alone will cause reciprocatory movement of said actuator to actuate the controller substantially as described.

6. A feeler for an automatic replenishing loom comprising a stand and means for securing the same to the loom, a bell crank lever mounted in said stand, an actuator mounted upon one arm of said bell crank lever, a bunter connected to the other arm of said bell crank lever, a feeler connected to said actuator and means for maintaining said bunter and said feeler in advanced or feeling position comprising helical springs engaging respectively said bell crank and said actuator and anchored to relatively stationary members.

In testimony whereof, I have signed my name to the specification, in the presence of two subscribing witnesses.

HENRY W. YOUNGQUIST.
